UNITED STATES PATENT OFFICE.

EDWARD W. SEAVERT, OF CAMAS, WASHINGTON.

SAWDUST-BURNER.

1,359,926.

Specification of Letters Patent. Patented Nov. 23, 1920.

Application filed September 19, 1917, Serial No. 192,100. Renewed August 25, 1920. Serial No. 406,007.

To all whom it may concern:

Be it known that I, EDWARD W. SEAVERT, a citizen of the United States, residing at Camas, in the county of Clark and State 5 of Washington, have invented new and useful Improvements in Sawdust-Burners, of which the following is a specification.

This invention relates to a sawdust burner designed for use in coal burning stoves of 10 the heating type commonly employing coal as fuel, the object of the invention being to provide a flue which may be disposed within the stove to render the same capable of using sawdust as fuel in an efficient, reliable 15 and economical manner.

A further object of the invention is to provide a flue which may be arranged within the stove in such a manner as to carry off the gases generated from the combustion of 20 the fuel within the fire pot, thereby eliminating all liability of an explosion, while permitting of a large amount of sawdust to be banked or stored within the stove for gravitational feed to the grate within the combustion 25 chamber.

The invention consists of the features of construction, combination and arrangement of parts, hereinafter fully described and claimed, reference being had to the accompanying drawing, in which:—

Figure 1 is a vertical front to rear section through a heating stove showing the application of the invention.

Fig. 2 is a perspective view of the gas flue 35 removed from the stove.

Referring to the drawing, 1 designates a heating stove of the type commonly employing coal as fuel, said stove including a base fire box or pot 2, an ash pit 3, a grate 4 arranged at the base of the fire box and top of the ash pit, a feed door 5 for the introduction of the fuel, a combustion chamber 6, and an outlet 7 for the discharge of the products of combustion.

45 In carrying my invention into practice, I provide a flue 8, made of metal or any other suitable material, said flue being arranged in an inclined position within the fire box and chamber 6 of the stove. As shown, the flue 8 is of conical form or tapers longitudinally, being of maximum diameter at the base and minimum diameter at the top and tapering uniformly from bottom to top throughout its length.

55 The base or enlarged end of the flue 8 rests upon the grate 4 at a point about centrally

of the grate, and the tube thence extends upwardly and rearwardly through the fire box to a point adjacent to the top of the chamber 6, and has its upper or reduced end arranged 60 to rest against the rear wall of the stove body approximately in vertical alinement with the smoke outlet 7. In practice, the tube may be retained in position by the charge of sawdust or fuel contained within 65 the stove, or it may be secured in place in any desired manner.

The flue 8 is imperforate throughout with the exception that the rear half or portion of the lower end of said flue is cut away oblique on a curved line, as shown at 9, forming a rear inlet opening for the passage into said tube of the gases generated from the combustion of the fuel within the fire box, said opening being substantially of the same 75 depth as the fire box. In the use of the tube the fire box and chamber 6 are filled with a charge 10 of sawdust up to a level just short of the top of the tube and the base of the door 5, the maximum level of the fuel being 80 such as to prevent any of the fuel from entering the upper end of the flue and permit of the free discharge of the gases from the upper end of the flue for final discharge through the outlet 7. In burning the fuel 85 with the use of the gas discharge flue, the lower portion of the body of fuel or that portion contained within the fire box 2, is ignited and as this portion of the fuel is gradually consumed and the residue drops 90 into the ash pit 3 the sawdust contained within the chamber 6 feeds downward by gravity to take the place of the fuel consumed, and this operation continues as long as the stove is kept in action or until the entire body of fuel is consumed, it being understood that the supply of fuel may be replenished from time to time as desired to maintain a maximum level, should it be desired to keep the stove in constant operation. 95

In the combustion of the fuel contained within the fire box gases are generated, and as these gases can not escape with sufficient freedom through the body of fuel above provision must be made for their escape in order to avoid an explosion. This danger of explosion is also increased in the event of the presence of any moisture in the fuel, resulting in the production of steam. By the use of the flue 8 a passage is provided for 110 the upflow of the gases and steam, if any, generated from the fire box in the upper

portion of the stove above the body of fuel, for discharge through the outlet 7, the gases passing into the flue through the cut away portion or incline as will be readily understood. By the use of a conical or flaring flue the upflow and discharge of the gases and steam is facilitated, with the result that all liability of the danger of explosion is obviated, while at the same time sufficient ventilation is afforded to insure free burning and proper combustion of the fuel, without liability of too rapid combustion, economy in the use of fuel thus being obtained.

It will be observed from the foregoing description that as the flue is imperforate except at its lower end, which is cut away to form an inlet of a depth substantially equal to that of the fire-pot, combustion of the fuel will be allowed to take place only within the fire-pot at the base of the body of fuel, that portion of the fuel resting upon the grate being only consumed, and the remainder of the fuel feeding down gradually to take the place of the fuel consumed, the residue from which flows through the grate into the ashpit. As the discharge end of the flue is located in proximity to and substantially in alinement with the smoke outlet 7, it will also be evident that a beneficial draft will be created through the tube, to facilitate combustion of the burning portion of the fuel and the rapid and safe discharge of gases, the depth of the inlet opening of the tube insuring the entering into the tube of all gases generated in the combustion zone, and thus obviating any dangerous tendency of these gases filtering up through the body of the fuel. Furthermore, the gases from the burning portion of the fuel will be conducted for discharge to a point above the maximum level of the fuel, allowing the burning portion of fuel to coke, with the result of burning more slowly and throwing off more intense heat, while obviating all liability of an explosion occurring through ignition of the gases. The described inclination of the flue and form of the gas inlet at the bottom thereof effectually prevents such inlet from becoming clogged or choked with the fuel, while, as the flue is otherwise entirely free from perforations, the entrance of sawdust at any point into the flue and choking of the flue will be entirely prevented. In the burning of sawdust with economy and safety, it is essential to restrict the combustion zone to the base portion of the mass of fuel, and to carry off the generated gases, otherwise the body of fuel at a higher elevation is liable to be ignited from the hot gases, with

the result of quickly consuming the whole body of fuel and causing dangerous overheating of the stove; or the admission of hot gases into the body of the fuel above its base is liable to cause the liberation of steam 65 or generation of an excess quantity of gas, with the consequent danger of explosion. By the provision of my improved construction of flue, all these objections and dangers are obviated in a simple and effective manner, its use allowing sawdust to be effectively burned as fuel in a safe and economical way.

By the use of my improved gas flue, which may be applied to any ordinary form of 75 coal burning heating stove, provision is made for utilizing an ordinarily refuse material of the character stated in a simple, convenient and efficient manner, and without danger of an explosion or other objection, while at the same time a draft of sufficient intensity is provided to insure the giving off of a volume of heat approximately equal to that afforded in the use of 80 coal as fuel.

Having thus fully described my invention, I claim:

In a sawdust burner for heating stoves, the combination with a heating stove having a fire-pot, an ash-pit, a grate between 90 the fire-pot and ash-pit, and a fuel chamber above the fire-pot provided with a fuel-feed door, said fuel chamber being also provided in its top and in proximity to its rear wall with an outlet for the discharge of the products of combustion, of a flue comprising a tube arranged to rest at its lower end upon the grate about centrally of the latter and to extend upwardly and rearwardly at an angle through the body of fuel in the fire-pot and fuel chamber with its upper end terminating above the maximum level of the fuel and in proximity to the rear wall of the fuel chamber and substantially in vertical alinement with said products discharge outlet, said tube being of maximum diameter at its lower inlet end, of minimum diameter at its upper outlet end, and tapering uniformly between such ends, the rear half of the said lower inlet end of the tube being cut away on a curved line to provide a gas and vapor inlet located wholly at the rear of said tube and of a depth approximately equal to the depth of the fire-pot, the tube being otherwise imperforate and 100 closed against communication with the fuel containing space of the stove throughout its entire length.

In testimony whereof I affix my signature.

EDWARD W. SEAVERT.
